(57) **CLAIM**

The ornamental design for a laser beam projector, as shown and described.

DESCRIPTION

FIG. 1 is a perspective view of a laser beam projector according to a new design claimed in this application ("claimed design");

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions depicted by broken lines in FIGS. 1 and 3-6 have been shown for the purpose of illustrating elements that form no part of the claimed design.

The claimed laser beam projector could interface with terminals such as a mobile phone, a tablet PC, a laptop computer etc. and is used for outputting images provided from the terminals.
